SKYLIGHT CONSTRUCTION

Abraham Ratner, East Orange, and Martin E.
Anderson, Newark, N. J.

Application September 30, 1936, Serial No. 103,268

1 Claim. (Cl. 108—16)

This invention relates to improvements in skylight constructions and one of its objects is to provide a skylight construction for a stage or platform of a building, theatre, school or similar place, with improved means for releasing gravity ventilating windows to drop to open position when a fire condition develops; improved means for seating each window so as to fully close the window opening; improved means for seating the joint at the upper edge of each gravity window or closure against the inflow of snow, sleet and rain, and of draining the rain water which tends to accumulate against the window joint; improved means for joining the edges of adjacent window panes to the steel framing, so that leakage is avoided; and improved means for connecting the spring curtain, employed for excluding natural illumination from the interior of the building, theatre, school or other place, so that the curtain will automatically open, so as to avoid interference with ventilation, when the gravity windows or closures are released to drop to open position.

With the above and other objects in view the invention consists in certain new and useful constructions, combinations, and arrangements of parts, clearly described in the following specification, and fully illustrated in the drawings, in which:

Fig. 1 is a view in elevation of the improved skylight construction, showing the operating cords connected in place, and the gravity windows or closures in closed positions.

Fig. 2 is a fragmentary enlarged vertical sectional view, showing one wing of the skylight.

Fig. 3 is a detail sectional view, slightly enlarged, showing the glass pane joint connection.

Fig. 4 is a detail side view, enlarged, showing the connector for the cable or cord of the spring wound curtain for excluding natural illumination, which cooperates with the restraining cable system used for controlling the gravity windows.

Fig. 5 is a detail vertical sectional view, enlarged, of the drain protecting device for the upper end of the window.

Referring to the drawings illustrating the practical construction of my skylight, 5 designates a roof support, which may be of any construction. On this base or roof support the angle steel 6 is mounted, and this is provided with a wedge shaped shim 7, against which is secured the window framing 8, also of steel or suitable fireproof construction, by means of the bolts 9.

The framing 8 provides a series of window openings 10, which are normally closed by the

metal windows or closures 11, which are hinged at 12 thereto. The framing 8 is supported in upwardly and outwardly inclined position, so that the windows or closures 11 will tend to drop by the force of gravity from closing positions to open positions, and each closure is provided with a cord or cable 13, secured at one end to the window or closure and at the other end to the framing, so that the opening action of the window or closure will be limited.

Above the framing 8 a steel angle member 14 is mounted in place on each side of the construction. On this member the steel angle 15 is mounted, and this is provided with a seat 16 to receive the window glass 17. To the member or angle piece 15 the steel member or lateral extension 18 is secured. The steel member 14 provides a horizontal sill for the windows, and may be faced on both sides with sheet copper 19, folded upon the same. The extension 18 is supported above the steel member 14, and a copper protecting sheet, or other cornice work 20, is secured thereto, as by the bolts or screws 21. The lower horizontal edge of this cornice member is formed with a longitudinal groove 22, which is disposed close to the lower horizontal bar 14a of the member 14. The upper edge of the closure or window 11 is equipped with a copper protector 23, which is formed with a longitudinal channel 23a, and provided with a doubled or folded longitudinal edge 23b, designed to stiffen the member.

Should rain water or the drippings from snow be blown or drain into the channel, this water or drippings will discharge through the holes 23c, formed in the bottom of the channel, which is disposed below the level of the upper edge of the window or closure, thus preventing the water or drippings from entering the small gap between the window and the framing 8.

Adjacent to the upper horizontal edge of the window glass or pane 17, a U-shaped channel member 25 is disposed. This channel member thus provides upstanding side flanges 25a and 25b. Over these flanges the copper drain strip 26 is mounted, and this strip is provided with longitudinal drain channels 26a and 26b, which extend outwardly of the channel member 25, so as to receive and drain off condensation which tends to accumulate against the inner side of the glass windows or panes 17.

A bolt 27 extends through the channel 25 and a felt cushioning washer 29 is engaged by a clamping nut 28. The bolt 27 extends between the edges of the panes 17 and 17a, and the flanges 25a and 25b have engagement with the panes at points

reasonably spaced from the marginal edges, so that chipping of the edges is prevented, and an effective joint is provided for the glass panes.

The channels 26a and 26b are designed to drain off toward the end of the skylight construction.

The overhead framing which supports the panes 17 and 17a is connected to the apex forming angle members 30 and 31, which are bolted to the intermediate strip or member 32 by the bolts 33, and which provide the downwardly and outwardly inclined flanges 34 and 35, upon which the overhead steel framing is secured by means of the bolts 36.

Steel work 37, in the form of suitable angle shapes is supported horizontally below the panes 17 and 17a, and over this steel work the protecting screen 38 is mounted in any suitable manner, to prevent broken glass from falling upon the stage located below.

On the steel work 37 a pulley block 39 is supported, as by the hook 40, adjacent to each gravity window closure 11, and over each pulley block a wire cable 41 is trained. This cable is connected by the loop 41a and the hook 41b to the eye 42a of the screw bolt 42. This bolt is threaded through the closure 11 and adjustably secured in place by means of the nuts 43. By adjusting the nuts 43 the tensional pull of the cable 41 upon the closure 11 may be varied at will, so that that closure 11 may be fully seated to completely seal the window opening.

All of the cables 41 are connected to a ring or connector 44, and this is again connected to the single cable 45, which is trained over the guide pulleys 46 and 47, and then connected to the plate or connector 48. This plate or connector 48 is again connected to a cable 49, which is wound upon the double hook 50. The cables 45 and 49 are preferable of textile or rope material. A knife 51 is supported adjacent to this combustible end of the control so that the cables 45 and 49 may be severed without untying the cord or rope wound in the hook 50.

The connector or plate 48 is equipped with an angular arm 52, to which the restraining cord or cable 53, of the spring windable curtain 54, which

is automatically wound upon the spring roller 55, is connected by winding. A fusible link 56 is provided on the cable 49, and another such fusible link is provided on the cable 45, so that should a fire start in the absence of attendants, the gravity opened window closures would be released. When the lower cable 49 is released either by manual action, or by the action of abnormal heat upon the fusible link, the cables restraining the gravity actuated closures and the spring wound curtain will be released, causing the curtain to be wound upon its spring roller and allowing all of the gravity actuated window closures to drop to open position, thus allowing full ventilation for the release of any smoke produced by the action of a fire within the building, and thereby complying with fire regulations.

When each window closure drops to open position the drain channel carried by its upper end will swing outwardly, clearing the steel work and the cornice work. Should one or more closures fail to fully seat the adjusting bolt connecting the restraining cable to the closure may be adjusted. But whatever adjustment is made between the individual restraining cable and its window closure, the automatic fire releasing action will not be hampered or complicated.

We claim as new and patentable:

A skylight construction consisting of a steel frame, a series of gravity opening closures mounted on the frame, a cable connected with each closure, a common connector for all of the cables, a cable connected with the connector, a spring wound shading curtain mounted to work under the closures, a cable connected to the curtain, a coupling device carried by the second named cable having an arm thereon on which the curtain cable may be restrained, a cable connected with said coupling device, and means for restraining the last named cable, whereby upon the release of said last named cable all of the gravity closures and the spring actuated curtain will be released.
